United States Patent Office.

EDWARD HOWELL, OF ASHTABULA, OHIO, ASSIGNOR TO HIMSELF AND P.
C. FORD, OF SAME PLACE.

Letters Patent No. 75,682, dated March 17, 1868.

IMPROVED THILL-STRAP.

The Schedule referred to in these Letters Patent and making part of the same.

TO ALL WHOM IT MAY CONCERN:

Be it known that I, EDWARD HOWELL, of Ashtabula, in the county of Ashtabula, and State of Ohio, have invented certain new and useful Improvements in Thill-Straps; and I do hereby declare that the following is a full and complete description of the same, reference being had to the accompanying drawings, making a part of this specification, in which—

Figure 1 is a side view.

Figure 2 is a front view.

Figures 3 and 4 are modifications of figs. 1 and 2.

Like letters of reference refer to like parts.

In the drawings, A represents the strap, the end of which is attached to the saddle of the harness. B is a metallic plate, connected to the strap A by means of bands or loops, a a, which pass around said strap, the ends being secured to the plate. The end of this plate is bent round, forming a loop, C, fig. 1. This loop is to receive the end of the thills, the belly-strap being attached to the link D resting in the loop, which loop is bent so as to receive the said link. E is a spring, to the upper end of which is attached a pin, e. This pin passes through a hole in the strap, as indicated by the dotted lines a', the other end of the spring being secured to the plate B.

This spring, provided with a pin, serves the place of the buckle commonly used, as the thill can be raised or lowered in the following manner: The spring can be pulled out, as indicated by the dotted lines E, fig. 1; thus removing the pin, and the loop C, which contains the end of the thill and forms part of the plate, can be raised or lowered, as desired, the pin being pushed into the holes d cut in the strap for that purpose.

Fig. 3 is a modification of fig. 1, as stated, and consists in making the loop C of wood, vulcanized rubber, &c., and lining the same with some softer material, as leather, J, to prevent abrasion. By the substitution of this material for iron, are avoided the rust and discoloring which naturally result from the use of iron, to the bad appearance of the harness if not to its injury.

The spring E in this strap is buried in the wood, out of the way or contact with the harness, and is pulled out by inserting the finger-nail in the cavity J', into which the end of the spring falls.

What I claim as my improvement, and desire to secure by Letters Patent, is—

The loop C, connected with the spring E, in combination with the pin e, strap A, and loops a a, substantially as and for the purpose set forth.

EDW'D HOWELL.
